UNITED STATES PATENT OFFICE.

DAVID SMITH, OF DURHAM, CANADA.

STRAW-CUTTER.

No. 825,426.

Specification of Letters Patent.

Patented July 10, 1906.

Application filed January 31, 1905. Serial No. 243,554.

To all whom it may concern:

Be it known that I, DAVID SMITH, of the town of Durham, in the county of Grey, in the Province of Ontario, Canada, have invented certain new and useful Improvements 5 in Straw-Cutters, of which the following is a specification.

My invention relates to improvements in straw-cutters adapted to be used in connection with threshing-machines or separately, as desired; and the object of the invention is to devise a straw-cutter which will cut the straw very fine and suitable for feed and with a minimum expenditure of power, which will 15 not be liable to choke or get out of order, in which the knives will require less attention than in an ordinary straw-cutter and yet may be readily adjusted when worn, in which the stationary knives will recede and consequently 20 any liability of breakage if undue pressure is put upon them or foreign matter gets in between them, and in which the knives may be readily thrown out of operation in case it is desired to leave the straw 25 uncut where it is desired to stack it; and it consists, essentially, of a main rotatable cutting-cylinder provided with knives arranged, preferably, radially opposite to each other and secured within suitable holders and a 30 coacting frame suitably hinged and provided with stationary knives and holders for the same secured in the frame, such frame being suitably supported and partially surrounding the cylinder and suitable conveyers extending 35 to the knives, the said knives being arranged as hereinafter more particularly explained.

Figure 1 is a distorted perspective view, looking from one side, of my straw-cutter, the 40 major portion of the frame and the opposite side being broken away. Fig. 2 is a sectional elevation of my straw-cutter. Fig. 3 is a cross-sectional elevation through the line *x y*, Fig. 2. Fig. 4 is a detail, partially broken 45 away, of the end holding-blocks for the cross-bars supporting the stationary knives. Fig. 5 is a distorted perspective detail of the block separating the knives. Fig. 6 is a detail of the central disk.

50 In the drawings like characters of reference indicate corresponding parts in each figure.

A is the main shaft of the rotating cylinder, which is journaled in suitable bearings A' on each side of the frame, only one side of the 55 machine being shown in Figs. 1 and 2, the machine being broken away intermediate of

its width. The side boards A² of the frame are also broken away, as indicated in Fig. 1.

B is the main cylinder, and B' designates the end disks of the same, such end disks being provided with reinforcing-rims b. The rims b have rectangular recesses b', located diametrically opposite to each other, and the rectangular recesses b², located diametrically opposite each other.

60 C represents cross-bars which extend at each end into the recesses b².

B² is a central disk secured on the shaft A and provided with the projections b³, arranged diametrically opposite to each other, 70 and the recesses b⁴ at each side thereof.

D represents channel-iron cross-bars with the channel to the inside, such channel-bars extending through the recesses b' of the disk B and the recesses b⁴ of the disk B².

75 2 represents blocks having notches 3 in the sides thereof, and 4 designates knives having the double cutting edges 4' 4''. The blocks fit into the channels of the channel-iron cross-bars D and are alternately arranged with the 80 knives 4 from the central disk B² to the outer disks B', being securely held in place by the longitudinal tie-rods 5, which are provided with nuts 5', fitting onto their threaded ends. The rods extend through the notches 3 of the 85 blocks.

In order to hold the knives from lateral displacement, I provide the L-bolts 6, which extend through the recessed portion of the rim b and over the end block 2, and in order 90 to hold the channel-iron bars in position in the recesses b' in the rims I provide the side bolts 7, which extend through the sides of the recesses into the channel-irons.

95 It will be noticed that the knives are arranged in two sets in the cylinder B, such sets being arranged radially opposite each other and held in place in the same way. The two sets of channel-iron bars are connected, preferably, by stays b⁵. The cylinder 100 is completed exteriorly by the substantially semicylindrical covers B³, which extend over the bars C and the channel-iron cross-bars D to the knives and are secured to the channel-iron cross-bars by screws or other suitable 105 means. The covers B³ serve to prevent the cylinders and knives thereof being choked up interiorly.

110 E represents the sides of the stationary knife-frame, which are pivotally supported on the cross-rods e, journaled in the side boards A², and are provided with upwardly-

extending horns E' and having end notches e' and inwardly and laterally extending projecting lugs e². The sides E are arranged in segmental form partially around the cylinder 5 B and are supported at the bottom by the inwardly-extending lips f of the brackets F. Each bracket F is held in place by the bolts f', extending through slots in the bracket and through the frame, and the set-screws f², 10 extending through the bent upper end F' of the brackets F, such set-screws projecting against the plate f³ on top of one of the longitudinal timbers, as indicated.

By means of the set-screws f² the brackets 15 F may be adjusted vertically, so as to set the stationary knives G, hereinafter referred to, nearer to or farther from the cylinder B.

In order to raise the stationary knife-frame clear of the cylinder when it is desired not to 20 cut feed, I provide a cord or chain e³, which passes around a drum e⁴, journaled in the sides A² of the frame, said cord being connected by a spiral spring e⁵ to the bottom of the sides E of the frame. There would of 25 course be two cords e³ provided, and the drum would be provided at the end with a crank-handle e⁶, whereby the cord may be wound up, so as to raise the frame. I also provide an auxiliary means for raising the frame, so 30 as to be able to raise the knives G clear should any obstruction pass between the stationary knives and the rotary knives. Such means consists of a cross-rod e⁷, having arms e⁸ thereon near the ends and pivotally connected by links e⁹ to lugs on the frame E. It 35 is desirable that this should be operated from the opposite or feeding side of the threshing-machine, so that the knives may be immediately relieved when desired. In order to effect this, I provide at the outer end of the rod e⁷ outside the side boards a suitable 40 double arm e¹⁰ and cords extending to the opposite end of the machine, as indicated by dotted lines, Fig. 2. It will thus be seen that 45 the frame may be raised slightly, when required, so as to relieve the coating stationary and rotary knives from an obstruction or foreign substance which might pass through between.

50 H represents the sides of the supplemental frame, which are provided with laterally-extending trunnions h, whereby they are journaled in suitable bearings at the bottom of the sides E. The upper ends of the sides H 55 are supported upon the lugs e² of the sides E and are connected together by a cross-bar H', secured by bolts h' to the top rib of the sides H of the supplemental frame.

h² represents brackets secured on the ends 60 of the bar H' and connected by arms h¹² to the cross-rods h³, which extend from notch e' to notch e' on the opposite side. The rod h³, the arms h¹², and the brackets h² serve with the bar H' to rigidly brace the frame at the 65 top, so that when the frame rises, should any

obstruction strike the knives G, it will rise evenly away from the cylinder B no matter where the obstruction or foreign substance may be located crosswise between the knives. In order to bring the stationary knives and supplemental frame down again, I provide a spiral spring H³ at each end, which is connected to the bracket h² and the horn E'. The bottom of the sides H of the supplemental frame are connected together by a cross-bar H⁴, as indicated, and the outer edge of the sides H of the supplemental frame are provided with a series of exterior recesses H⁵ and H⁶ and bracing cross-boards H⁸ and H⁹, secured to the edge of the side by suitable 80 bolts.

The sides H preferably have reinforced or ribbed outer edges, as indicated, and beneath these edges are secured the angular deflecting-plates h⁷, h⁸, and h⁹, which serve to guide the 85 cut feed through the knives.

The knives G are secured between blocks 2' and are held by channel-iron cross-bars D' exactly the same as the knives 4. The ends of the channel-bars D' and blocks carrying 90 each set of knives are held in hollow blocks D², which are located in the recesses H⁵, H⁶, and H⁷. Each set of knives is held at the same way, and I shall simply describe the 95 manner of holding and adjusting the knives in the one recess—i.e., the top one, H⁵. The top of the end block D² is provided with an arc-shaped projection d, having a tapered hole d'.

d² is a slotted hole in the bottom side of the 100 hollow block.

d³ is a flange extending out beyond the reinforcing-rib and provided with a cross-notch d⁴.

d⁵ is a bolt the square head of which fits 105 into the notch d⁴. The bolt d⁵ extends upwardly through the flange d³, the slot d², and hole d' and is provided with a nut at the upper end.

d⁶ and d⁷ are set-screws extending through 110 the ribbed sides of the recess H⁵ and designed to contact with the bottom of the block D².

d⁸ is a plate which is held against the head of the bolt d⁵, so as to hold it from turning in its cross-notch d⁴.

d⁹ and d¹⁰ are set-screws passing through 115 the ribbed sides of the recess H⁵ and designed to contact with the sides of the block D².

By adjusting the set-screws d⁶ and d⁷, as well as the set-screws d⁹ and d¹⁰, the end blocks D² may be tilted as desired, so as to give the proper draw to the stationary set of knives G in relation to the rotating set of knives 4. The three sets of knives G may be given such a desired forward tilt as may 120 be found most conducive to the best results, and each stationary set of knives coacts with the rotating set of knives, they being so placed that the knives of the rotating sets 125 pass between the knives of the stationary sets. 130

I is the straw-deck, provided with the discharging-fingers *i*, and J is the endless conveyer, suitably supported and driven and provided with cross-bars *j*, having feeding-fingers *j'*.

K is an endless conveyer suitably driven and supported and provided with cross-slats *k*, having the feeding-fingers *k'*, as indicated. It will be noticed that the fingers *k'* are longer than the fingers *j'*.

By means of the fingers *j'* and *k'* the straw is fed to the knives, which, rotating at a high rate of speed, effectually and finally chop the straw into a suitable condition for feed.

15 Should any obstruction meet the knives, the supplemental frame, comprising the sides H and their connecting cross-bars, will recede, carrying the knives G away from the knives 4 and allowing such obstruction to 20 pass through. If the obstruction is larger than will allow of the obstruction to pass through, the horns H¹⁰ on the upper portion of the supplemental frame will strike the bottom of the arms e⁸, and thereby break the 25 joint between arms e⁸ and bar e⁹ and cause the carrying-frame comprising the sides E and their coacting cross-bars to rise upwardly on the pivot e and allow of the obstruction to pass through.

30 As hereinbefore described, if it is not desired to cut feed the frame, comprising the sides E and their connecting-bars, may be raised.

In order to adjust or relieve the stationary 35 rotary knives, all it is necessary to do is to loosen the nuts on the ends of the rods, holding the rods and intervening blocks tightly together, when the knives may be adjusted and withdrawn or reversed, as may be desired.

What I claim as my invention is—

1. In a straw-cutter, the combination with the rotating cylinder provided with substantially radially-arranged knives, of a frame 45 partially encompassing the cylinder and provided with a series of sets of stationary knives between which the rotary knives rotate, the said frame being pivotally supported at the top at the feeding end and slotted bars provided with turned-in lips on which the lower end of the frame rests, bolts extending through the slots in the bars and a set-screw extending through the bent upper end of the bar and resting on the frame as and for the 50 purpose specified.

2. In a straw-cutter, the combination with the rotating cylinder provided with substantially radially-arranged knives, of a main frame partially encompassing the cylinder 55 and comprising the sides and connecting cross-bars, a rod upon which the frame is pivoted at the top, a support for the frame at the bottom and a supplemental frame comprising sides and connecting cross-bars, the sides being provided with trunnions jour-

naled in bearings in the sides of the aforesaid main frame and the said supplemental frame partially encompassing the cylinder, and lugs projecting from the sides of the aforesaid main frame and projecting under the top 70 of the sides of the supplemental frame and stationary knives carried by the supplemental frame as and for the purpose specified.

3. In a straw-cutter, the combination with the rotating cylinder provided with substantially radially arranged knives, of a main frame partially encompassing the cylinder and comprising the sides and connecting cross-bars, a rod upon which the main frame is pivoted at the top, a support for the frame 80 at the bottom and a supplemental frame comprising sides and connecting cross-bars, the sides being provided with trunnions journaled in bearings in the sides of the aforesaid main frame and the said supplemental 85 frame partially encompassing the cylinder, lugs projecting from the sides of the aforesaid main frame and projecting under the top of the sides of the supplemental frame and stationary knives carried by the supplemental 90 frame, the cross-rod extending through the side boards of the machine, the depending arms, the links pivotally connected to the bottom of the arms and the sides of the main encompassing frame and the horns of the 95 supplemental frame designed to come in contact with the bottom of the said arms to break the joint when the cross-rod is partially rotated as and for the purpose specified.

4. The combination with the rotating cylinder and the substantially radially arranged sets of alined knives, of the encompassing frame suitably supported and the supplemental frame supported on the encompassing frame and provided with peripheral recesses 100 and the sets of stationary alined knives suitably supported in said recesses and means for tilting each set as and for the purpose specified.

5. In a straw-cutter, the cutting-cylinder 110 comprising the end disks having peripheral recesses therein, the channel-iron cross-bars fitting each side of the recesses, the alined knives, the intervening blocks extending into the channel-iron cross-bars and means for 115 holding the blocks and knives securely together as and for the purpose specified.

6. In a straw-cutter, the cutting-cylinder comprising the end disks having peripheral recesses therein, the channel-iron cross-bars 120 fitting each side of the recesses, the alined knives, the intervening blocks extending into the channel-iron cross-bars and having side notches and the rods extending through the blocks and provided at the end with suitable 125 nuts as and for the purpose specified.

7. In a straw-cutter, the cutting-cylinder comprising the end disks having peripheral recesses therein, the channel-iron cross-bars fitting each side of the recesses, the alined 130

- knives, the intervening blocks extending into the channel-iron cross-bars and having side notches, the rods extending through the blocks and provided at the end with suitable 5 nuts and the intermediate stays connecting the channel-iron cross-bars in the opposite recesses as and for the purpose specified.
8. In a straw-cutter, the cutting-cylinder comprising the end disks having peripheral 10 recesses therein, the channel-iron cross-bars fitting each side of the recesses, the alined knives, the intervening blocks extending into the channel-iron cross-bars and having side notches, the rods extending through the 15 blocks and provided at the end with suitable nuts, the L-shaped bolts extending through the inner sides of the recesses and projecting over the end blocks as and for the purpose specified.
10. In a straw-cutter, the cutting-cylinder comprising the end disks having peripheral recesses therein, the channel-iron cross-bars fitting each side of the recesses, the alined knives, the intervening blocks extending into the channel-iron cross-bars and having side notches, the rods extending through the 25 blocks and provided at the end with suitable nuts, and the bolts extending through the sides of the recesses into the channel-iron 30 cross-bars as and for the purpose specified.
10. In a straw-cutter, the cutting-cylinder comprising the end disks having peripheral recesses therein, the channel-iron cross-bars fitting each side of the recesses, the alined 35 knives, the intervening blocks extending into the channel-iron cross-bars, means for holding the blocks and knives securely together and the semicylindrical encompassing covers for the cylinder as and for the purpose specified.
11. The combination with the supplemental frame, of a set of stationary alined knives and channel-iron cross-bars and intervening blocks and means for holding the ends 40 of the bars in place and means for tilting the ends of the bars as and for the purpose specified.
12. The combination with the supplemental frame, of a set of stationary alined 45
- knives and channel-iron cross-bars and intervening blocks, the hollow end blocks into which the channel-iron bars and intervening blocks fit and means for securing the intervening blocks and knives together and holding them within the hollow end blocks as and 50 for the purpose specified.
13. The combination with the supplemental frame comprising sides having recesses located opposite to each other, of the alined sets of knives, means for holding them 55 together, the end blocks within which such means extend provided with arc-shaped upper projections and tapered hole through the projection, and a slot in the lower side of the block, set-screws extending through the re- 60 inforcing edge of the sides, set-screws extending through the flanges underneath the end blocks and plates through which such set-screws extend, and bolts fitting in notches in the flanges and extending up through the slots 65 in the end blocks and the tapered hole in the arc-shaped projection on the top of the end blocks as and for the purpose specified.
14. In a straw - cutter, the combination with the main encompassing frame provided 70 with upwardly-projecting horns having end notches, of the supplemental frame comprising the sides and connecting cross-bars, the bracket secured to the upper cross-rod, a cross-rod fitting in the notches in the horns 75 aforesaid, and the arms connecting the brackets to said cross-rod as and for the purpose specified.
15. In a straw - cutter, the combination with the main encompassing frame provided 80 with upwardly-projecting horns having end notches, of the supplemental frame comprising the sides and connecting cross-bars, the brackets secured to the upper cross-bar, a cross-rod fitting in the notches in the horns 85 aforesaid, and the arms connecting the brackets to said cross-rod and the springs connecting the brackets to the horns as and for the purpose specified.

DAVID SMITH.
